PULP SCREEN

Wilfred F. Mathewson, Boston, Mass., assignor to
Mathewson Machine Works, Inc., Quincy,
Mass., a corporation of Massachusetts

Application May 20, 1952, Serial No. 288,820

16 Claims. (Cl. 92—35)

1

This invention relates to pulp screens, and especially to pulp screens of the type shown in my Patents #2,450,838, October 5, 1948, and #2,525,701, October 10, 1950.

The pulp screen shown in each of said patents comprises two concentrically arranged cylindrical screening elements forming between them an annular clearance space of a size to permit the acceptable portion of unscreened pulp to pass therethrough, but of insufficient size to allow the unacceptable portion of such pulp to pass therethrough. One of the two screening elements is provided with a plurality of slots which extend parallel to the axis of said element and provide passages from the outside of the element into said clearance space. Said screening element is also provided with a plurality of grooves which are parallel to the slots and which are open to the clearance space. Preferably the slots and grooves are alternately arranged.

The screening operation involves the passage of the unscreened pulp through the slots into the clearance space and the flow of the acceptable portion of said pulp through the clearance space into the grooves which have communication with a chamber in which the screened pulp is received. Preferably one at least of the screening elements is rotated about its axis during the pulp-screening operation.

When the slots are tapered, as shown in Patent #2,525,701, they are liable to become clogged by either coarse, unacceptable portions of the pulp stock or flocks resulting from flocculation of the pulp which enter the outer wide inlet edge of a slot but which are too large to pass through the narrow inner discharge edge of the slot which is open to the clearance space.

One of the objects of the present invention is to provide novel means for periodically clearing each tapered slot not only of any coarse or unacceptable portion of the pulp stock, but also of any flocculated pulp which may become lodged therein.

Another object of the invention is to provide means for thus clearing the slots of any coarse material or flocculated pulp which may become lodged therein by means of blades which are periodically inserted into the slots.

A still further object of the invention is to provide a novel mounting for the rotatable screening element which includes a floating bearing by means of which the clearance between the screening elements is maintained constantly with the proper dimension.

Other objects of the invention are to improve

2

pulp screens in various particulars which will be hereinafter pointed out.

In the drawings wherein I have illustrated a selected embodiment of my invention:

Fig. 1 is a sectional view taken on substantially the line 1—1, Fig. 2, the screening units being shown in plan view;

Fig. 2 is a section on the line 2—2, Fig. 1;

Fig. 3 is a section on the line 3—3, Fig. 2;

Fig. 4 is a vertical sectional view through the lower portion of one of the screening units;

Fig. 5 is a section on the line 5—5, Fig. 6;

Fig. 6 is an enlarged section through one of the screening units on the line 6—6, Fig. 5.

Fig. 7 is a section on the line 7—7, Fig. 6.

The pulp screen herein illustrated comprises a casing 1 having an inlet opening 2 to receive unscreened pulp, and a plurality of screening units 3 located within said casing. Each screening unit comprises an inner cylindrical screening element 4 and an outer cylindrical screening element 5 which is concentric with the inner screening element 4, said screening elements providing between them an annular clearance space

25 which is of a size to permit the acceptable portion of unscreened pulp to pass therethrough, but which is insufficient in size to permit any coarse or unacceptable portion of such pulp to pass therethrough.

30 The outer screen element 5 is provided with a plurality of radial slots 7 which extend parallel to the axis of said screen element and provide passageways through which unscreened pulp in the casing 1 may flow into the clearance space 6.

35 The outer screen element 5 is also provided with a plurality of grooves 8 which are open to the clearance space and which extend parallel to the slots 7. As in the devices of the patents above referred to, the screening of the pulp results from the flow of the pulp through the slots 7 into the clearance space 6, and through said clearance space into the grooves 8. The dimension of the clearance space is such that only the acceptable portion of the unscreened stock will 40 pass therethrough into the grooves 8, and hence the pulp which flows into the grooves 8 will be properly screened.

45 The grooves 8 communicate at their upper ends with an upper chamber 9 with which the casing 50 is provided, and the lower ends of the grooves 8 communicate with a lower chamber 10 also located within the casing 1. The two chambers 9 and 10 communicate with a discharge duct 11 which leads to a discharge opening 12.

55 Each of the screening units 3 within the casing

has the construction above set forth, and the upper end of the discharge grooves 8 of all of the screening units 3 deliver the screen pulp into the upper chamber 9 and the lower ends of said discharge grooves 8 deliver the screened pulp into the lower chamber 10.

All of the screening units are thus supplied with unscreened stock through the inlet opening 2, and the screened stock or pulp from all of the screening units is delivered through the discharge opening 12.

In the device shown in the drawings, the outer screening element 5 of each screening unit is mounted for rotation about its axis, and similarly the inner screening element 4 of each screening unit is mounted for rotation.

The upper end of the outer screening element 5 of each screening element has a bearing 14 in the partition member 13 which divides the upper chamber 9 from the interior of the casing 1 in which the screening units operate (see Figs. 5 and 7). The lower end of each screening element 5 is connected to a depending bearing sleeve 15 which is mounted in the portion 16 of the supporting frame on which the casing 1 rests, said bearing sleeve having a gear 17 fast thereon by which it can be turned. The bearing sleeve 15 is shown as being connected to the outer screening element 5 by means of a pin connection 18, shown in Fig. 7, the upper end of the bearing sleeve having the flange 19 which carries the pin 18, and the lower end of the outer screening element 5 having a socket 20 in which the pin is received.

The inner screening element 4 has a bearing 21 in the upper end of the outer screen element, each inner screen element having a closed upper end 22. The lower end of each inner screen element 4 is connected by a pin connection with a hollow shaft 23 which fits and has a bearing in the sleeve 15, as shown in Fig. 2. The lower end of the hollow shaft 23 has a bearing in the portion 24 of the supporting framework. Mounted on the hollow shaft 23 below the bearing sleeve 15 is a gear 25 by which the inner screen member 4 may be rotated. The pin connection between the hollow shaft 23 and the inner screen member 4 is formed by one or more pins 26 which are mounted in the upper end of the hollow shaft 23 and extend into a socket 27 with which the inner screen member 4 is provided, as shown in Fig. 7.

In the operation of a pulp screen of this type it is important that the clearance space 6 should be maintained with a constant dimension, and to provide for this not only the upper end of the inner screen member 4 but also the central portion and the lower end thereof have a bearing in the outer screen member 5. As shown in Fig. 7, the lower end 28 of the inner screen member is rotatably mounted in the portion 29 of the outer screen member 5, and a bearing 60 is provided between the inner and outer screen members at the central portion thereof. Hence said inner and outer screen members are compelled to turn accurately about the same axis, and the width of the clearance space will remain constant.

The lower end of the outer screen member 5 is mounted in a floating bearing which includes a ring 30 of yielding material that surrounds and is retained in a groove formed in the lower portion 71 of the outer screening element 5 and is received between two retaining rings 78 rigid with the bottom of the casing 1. The lower portion 71 of the screening element 5 is spaced slightly from the inner edges of the retaining ring 78 and

the resilient character of the ring 30 permits a slight radial movement of the lower ends of the screening elements. This construction, together with the pin connections 18 and 26, provide for free rotative movement of the screening elements even if the axis about which said elements are rotating is not precisely in line with the axis of the shafts 23 and 15.

In the operation of the device the inner and outer elements 4 and 5 of each screening unit rotate at slightly different speeds. The inner screen element 4 is hollow and is provided with a plurality of openings 31 leading from the clearance space 6 into the interior of said screen element. During the relative rotation of the inner and outer screen elements each opening 31 will be brought into register with the tapered slots 7 successively, and if any flock or unacceptable portion of the pulp stock begins to accumulate in any slot such material may be flushed through an opening 31 when it comes into registry with the clogged slot, and thus the material which was clogging the slot will be delivered into the interior of the inner screen member 4. This unacceptable material or "tailings" will flow through the hollow shaft 23 into a lower chamber 32 in which the "tailings" from all of the various screening units 3 are delivered, and such tailings will be delivered from the chamber 32 through a suitable discharge outlet 33.

Any suitable means may be employed for rotating the inner and outer screen elements of each screening unit. As shown in Figs. 2 and 3, the gear 17 by which the outer screen element 5 of each screening unit is rotated meshes and is driven by a central gear 34 mounted on a shaft 35 that is supported in suitable bearings 36. The gear 34 is driven by a pinion 35a carried on a vertical shaft 36a mounted in the supporting frame on which the casing 1 is carried. Said shaft 36a has at its lower end a sprocket wheel 37 around which passes a sprocket chain 38 that is driven by a sprocket on a shaft 39. The shaft 39 carries a large pulley 40 which is driven by a belt 41 from the shaft 42 by a suitable motor 43.

Each gear 25 by which the inner screen element of each screening unit is rotated meshes with and is driven by a second large gear 44 which is mounted for rotation on the shaft 35. The shaft 39 carries a pinion 45 which meshes with and drives the gear 44 and by this means the two gears 44, 34 will be driven at different speeds.

While the flushing openings 31 with which the inner screen element 4 of each screening unit is provided are useful in flushing the inlet slots 7 in case any slot begins to clog, yet these flushing openings are not always completely successful in keeping the slots 7 free, and I have, therefore, provided a mechanical means in the form of a blade which periodically is thrust into each slot 7 of each of the screening units, and thereby forcibly clears from the slot any material which may be clogging said slot. The slot-clearing movement of the clearing blade is preferably so timed with relation to the rotation of the inner screen element 4 that during the time said blade occupies any slot, an opening 31 in said inner screen element will move past and thus come into direct communication with the discharge edge 70 of said slot, so that any material which is clogging the slot will be forcibly thrust through the slot and into and through the flushing opening 31 by the blade.

In the construction herein shown, the shaft 35 extends upwardly through the casing and the

upper end is supported in a bearing 36 carried by the partition 13. There are two clearing blades 45 carried by the upper portion of the shaft 35, said blades being oppositely disposed. Each blade is mounted in a blade-supporting member 46 and the two blade-supporting members 46 are carried by arms 47 that are secured to and extend from the shaft 35.

In order not to unduly weaken the outer screening member 5, the slots 7 therein are made in sections 7a, the circumferential portion 48 of the outer screen member between each two adjacent series of slot sections 7a being solid.

The blades 45 are provided with operative blade sections 45a, each blade section having a length corresponding to a slot section 7a. Each clearing blade is mounted in a head 49 which is received in a vertical recess 50 with which the blade-supporting member 46 is provided. The head 49 is formed with a plurality of stems 51 which extend through the supporting member 46 and each of which is screw threaded at its outer end to receive check-nuts 52. The head 49 is acted upon by springs 53 which encircle the stems 51 and yieldingly hold the head 49 with its blade 45 in operative position. If during the operation of the machine a blade 45 enters a clogged slot 7 at a time when there is no opening 31 in communication therewith, the material clogging the slot will be forced inwardly toward the inner edge of the slot but cannot be pushed therethrough. In such case the springs 53 provide for a backward yielding movement of the blade and thus prevents injury to the blade or the screening unit.

It will be noted that the screening units 3 are arranged in an arc within the casing 1 and the shaft 35 is located at the center of said circle and is thus equidistant from all of the screening units.

The rotative movement of the shaft 35 and that of the outer screening member 5 of each screen unit have such a relation that as said shaft rotates each blade 45 will enter a slot 7 of the outer screen members of the various screening units in succession, each blade section 45a entering one of the slot sections 7a. The walls of the slot sections 7a diverge from the clearance space space 6 to the outer periphery of the screening element 5, so that as said element 5 and the blade sections 45a rotate, said blade sections will mesh with the slot sections in much the same way as the teeth of a pair of gears mesh with each other.

As a result, the rotary movement of the outer screening elements of the various screening units and that of the shaft 35 will cause each blade section 45a to enter and clear a slot section 7a and then to be withdrawn from the slot section.

The timing of the gearing which rotates the outer screening elements 5 and the shaft 35 is preferably such that at each rotation of said shaft the blade sections 45a are thrust into and clear the slot sections of a different slot 7 of each screening unit, and thus as the rotation of the screening elements 5 and the shaft 35 continues each one of the slots 7 of each screening unit will in turn have received a blade 45 and will thus be freed from any unacceptable material or flocculated pulp which may have become lodged therein.

Because of the different speeds at which the inner and outer screening elements 4, 5, of each screening unit 3 rotate, an opening 31 of each inner element will move periodically into com-

munication with each slot 7 of the corresponding outer screening element 5, and by properly timing the relation between the rotary motion of the shaft 35 carrying the blades 45 and the rotary motion of the inner screen member 4, an opening 31 of said inner member will be moved into communication with each slot 7 of the corresponding outer screen member while said slot is being cleared by a blade.

10 I claim:

1. A pulp screen comprising two concentrically arranged screening elements forming between them an annular clearance space of a size to permit acceptable portions of pulp stock to pass therethrough but of insufficient size to permit unacceptable portions of said stock to pass therethrough, the outer screening element having a plurality of inlet slots leading to said clearance space through which pulp to be screened is delivered thereto, and also having a plurality of discharge grooves extending parallel to the slots and open to said clearance space, whereby acceptable portions of the pulp stock may pass through the inlet slots to the discharge groove through the clearance space, a chamber communicating with all of said discharge grooves and into which the screened stock is delivered through said grooves, a slot clearer having a blade, and blade-actuating means to move the blade periodically into each inlet slot to remove therefrom any accumulated pulp stock which is clogging said slot.

2. A pulp screen comprising two concentrically arranged screening elements forming between them an annular clearance space of a size to permit acceptable portions of unscreened pulp stock to pass therethrough but of insufficient size to permit unacceptable portions of said stock to pass therethrough, the outer screening element having a plurality of inlet slots leading to said clearance space, and also having a plurality of discharge grooves extending parallel to said slots and open to the clearance space, whereby acceptable portions of the pulp stock may pass from the inlet slots to the discharge grooves through the clearance space, a chamber communicating with all of the discharge grooves into which the screened stock is delivered, means to rotate said outer screening element, a slot clearing blade, and blade-actuating means to move said blade periodically into each slot as the outer screen element rotates, thereby to remove from the slot any accumulated pulp stock.

3. A pulp screen as defined in claim 2 and in which the blade-actuating means moves said blade into the various slots in a predetermined order, thereby to clear said slots of any accumulated pulp stock which tends to clog them.

4. A pulp screen as defined in claim 2 which includes means mounting the slot-clearing blade for rotation about an axis parallel to that of the outer screen element and so situated that at each rotation of the blade it is moved into and then withdrawn from one of the inlet slots, and means to rotate the blade about its axis in timed relation with the rotation of the screening element.

5. A pulp screen comprising two concentric cylindrical screening elements forming between them a clearance space of a size to permit acceptable portions of unscreened pulp stock to pass therethrough but insufficient in size to permit unacceptable portions of said stock to pass therethrough, the outer screening element having inlet slots extending therethrough from its outer face to the clearance space, and also having discharge grooves extending parallel to the slots and open

to the clearance space, whereby the acceptable portions of the pulp stock may pass from the inlet slots into the discharge grooves through the clearance space, a chamber communicating with all the discharge grooves and into which said screened pulp is delivered, means to rotate the outer screening element about its axis, a shaft situated exterior to the outer screening element and parallel to its axis, a plurality of slot-clearing blades carried by said shaft, each blade adapted upon each rotation of the shaft to enter and then be withdrawn from a slot, thereby clearing said slot from any pulp stock accumulated therein, and means to rotate said shaft in timed relation with the rotation of the outer screening element.

6. A pulp screen comprising two concentric cylindrical screening elements forming between them an annular clearance space of a size to permit acceptable portions of unscreened stock to pass therethrough but insufficient in size to permit unacceptable portions of such stock to pass therethrough, the outer screening element having inlet slots extending therethrough and leading to the clearance space and also having a plurality of discharge grooves extending parallel to the slots and open to the clearance space, a chamber communicating with all the discharge grooves and into which the screened stock received by the grooves is delivered, said inner screening element having an interior chamber communicating with a tailings outlet and also having a flushing opening leading from the clearance space to said chamber, means to rotate the outer and inner screening elements at different speeds whereby the slots are brought successively into communication with said flushing opening, a slot-clearing blade, and blade actuating means to move said blade periodically into each slot at a time when said slot is in communication with said flushing opening, whereby any accumulated pulp stock which has become lodged in said slot is forced therethrough and into and through said flushing opening.

7. A pulp screen as defined in claim 6 in which the inner screening element has a plurality of flushing openings leading from the clearance space to said interior chamber, and which includes blade-actuating means to move the slot-clearing blade into each slot at a time when said slot is in communication with one of the flushing openings.

8. A pulp screen as defined in claim 6 in which the inner screening element is provided with a plurality of flushing openings leading from the clearance space to said interior chamber, and which includes a plurality of slot-clearing blades and blade-actuating means to move each blade into an inlet slot at a time when said slot is in communication with a flushing opening.

9. A pulp screen comprising two concentrically arranged cylindrical screening elements forming between them an annular clearance space of a size to permit acceptable portions of unscreened pulp stock to pass therethrough but insufficient in size to permit unacceptable portions of said stock to pass therethrough, the outer screening element having inlet slots extending therethrough to the clearance space, and also having discharge grooves extending parallel to the slots and open to said clearance space, a chamber communicating with all the discharge grooves and into which the screened pulp stock is delivered, said inner screening element having an interior chamber communicating with a tailings outlet,

and also having a plurality of flushing openings leading from the clearance space to said chamber, means to rotate the outer and inner screening elements at different speeds whereby each slot is brought into communication with the flushing openings successively, a rotary blade-supporting shaft parallel to the axis of the screening elements, means to rotate said shaft, a slot-clearing blade mounted on said shaft and adapted during the rotation thereof to move into and out of each inlet slot periodically at the time said slot is in communication with a flushing opening.

10. A pulp screen as defined in claim 9, and which includes a plurality of slot-clearing blades carried by the shaft and each adapted during the rotation of the shaft and the inner and outer screen elements to be moved into and out of each inlet slot while it is in communication with a flushing opening.

11. A pulp screen comprising a casing having an inlet opening through which unscreened pulp stock is delivered, a plurality of individual screening units situated within said casing and arranged in circular formation and all located at the same distance from a common center, each screening unit comprising two concentrically arranged cylindrical screening elements forming between them a clearance space of a size to permit acceptable portions of the pulp stock to pass therethrough but insufficient in size to permit unacceptable portions of said stock to pass, the outer screening element of each screening unit having a plurality of inlet slots extending therethrough and communicating with the clearance space thereof, and also having a plurality of discharge grooves open to the clearance space, said casing having a chamber with which all of the discharge grooves of all of the screening units have communication and into which the screened pulp from all of the screening units is delivered, means to rotate the outer screening element of each screening unit, a slot-clearing blade, and blade-actuating means to move said blade into and out of a slot in each of the screening units in succession.

12. A pulp screen as defined in claim 11 and which includes a rotary shaft located at the center of the circularly arranged screening units, two oppositely disposed slot-clearing blades mounted on said shaft and adapted during the rotation of the shaft to enter and to be withdrawn from a slot in each rotating slotted screening element, and means to rotate the shaft in timed relation with the rotary movement of the slotted screening element.

13. A casing having an inlet opening through which unscreened pulp stock is delivered thereto, and also having a tailings outlet, a plurality of screening units situated within said casing and arranged in an arc about a common center, each screening unit comprising two concentrically arranged cylindrical elements forming between them a clearance space, the outer screening element of each screening unit having a plurality of inlet slots extending therethrough and communicating with the clearance space, and also having a plurality of discharge grooves which are open to the clearance space, said casing having a chamber with which all of the discharge grooves of all of the screening units have communication and into which the screened pulp from all of the said grooves is delivered, the inner screening element of each screening unit having an interior chamber and a flushing opening forming a communication between the clearance space

9

and said chamber, means to rotate the inner and outer screening elements of each screening unit at different speeds, whereby the flushing opening of each inner screening element is brought into direct communication with the slots of the corresponding outer element successively, a shaft situated coaxial with said common center, means to rotate said shaft, a slot-clearing blade mounted on said shaft and adapted during the rotation of the shaft to enter and to be withdrawn periodically from each slot in each rotating slotted screening element at a time when said slot is in communication with a flushing opening, and means providing a communication between the interior chamber of each inner screening element and said tailings outlet.

14. A pulp screen comprising a casing having an inlet opening through which unscreened pulp stock is delivered, a plurality of separate screening units situated within said casing and arranged in circular formation, each screening unit comprising two concentrically arranged cylindrical screening elements forming between them a clearance space of a size to permit acceptable portions of the pulp stock to pass therethrough, but insufficient in size to permit unacceptable portions of such stock to pass therethrough, the outer screening element of each screening unit having a plurality of inlet slots extending therethrough and communicating with the clearance space thereof, and also having a plurality of discharge grooves open to the clearance space, said casing having a chamber with which all of the discharge grooves of all of the screening units have communication and into which the screened pulp from all of the screening units is delivered, the inner screening element of each screening unit having an interior chamber and also having a flushing opening leading from the clearance space to said chamber, said casing having a tailings outlet with which the interior chambers of all of the screening units communicate, means to rotate the outer and inner screening element of each screening unit at different speeds, whereby the slots in the outer screening element of each screening unit are brought successively into communication with the flushing opening of said unit, and means common to all of the screening units to clear each slot of the outer screening element of each screening unit at a time when said slot is in communication with the flushing opening of said unit.

10

15. A casing having an inlet opening through which unscreened pulp stock is delivered thereto, a plurality of screening units situated within said casing and arranged in an arc about a common center, each screening unit comprising two concentrically arranged cylindrical elements forming between them a clearance space, the outer screening element of each screening unit having a plurality of inlet slots extending therethrough and communicating with the clearance space and also having a plurality of discharge grooves which are open to the clearance space, said casing having a chamber with which all the discharge grooves of all the screening units have communication and into which the screened pulp from all of said grooves is delivered, means to rotate each outer screening element, and means common to all the screening units to clear periodically each inlet slot of the outer screening element of each screening unit.
16. A casing having an inlet opening through which unscreened pulp stock is delivered thereto, a plurality of screening units situated within said casing and arranged in an arc about a common center, each screening unit comprising two concentrically arranged cylindrical elements forming between them a clearance space, the outer screening element of each screening unit having a plurality of inlet slots extending therethrough and communicating with the clearance space and also having a plurality of discharge grooves which are open to the clearance space, said casing having a chamber with which all the discharge grooves of all the screening units have communication and into which the screened pulp from all of said grooves is delivered, means to rotate each outer screening element, and mechanical means common to all the screening units to clear periodically each inlet slot of the outer screening element of each screening unit, and to clear in succession an inlet slot in each of the outer screening elements.
